UNITED STATES PATENT OFFICE

JOHN F. O'CONNOR, OF CHICAGO, ILLINOIS, ASSIGNOR TO W. H. MINER, INC., OF CHICAGO,
ILLINOIS, A CORPORATION OF DELAWARE

HAND BRAKE

Application filed January 27, 1930. Serial No. 423,573.

This invention relates to improvements in hand brakes.

One object of the invention is to provide a simple and efficient hand brake mechanism, especially adapted for railway cars, wherein all of the operations are controlled by a single manually actuated means, operation of the same in one direction effecting tightening of the brakes and operation in a reverse direction effecting complete release of the brakes with free running of the tightening element.

A further object of the invention is to provide a hand brake mechanism of the character indicated, including a rotary chain winding means, a rotary operating element adapted to be engaged and disengaged from said winding means, a locking dog cooperating with said operating means to hold the same against rotation in a direction corresponding to the direction of rotation thereof while the chain is being wound on the tightening means to tighten the brakes, and permitting movement thereof in a chain winding direction, and means cooperating with said operating means and actuated by rotation in reverse directions of said operating means for moving the same into operative engagement with the chain winding means to effect tightening of the brakes and disengaging the same therefrom to permit free running of the chain winding drum and complete release of the brakes.

Other objects of the invention will more clearly appear from the description and claims hereinafter following.

In the drawings, forming a part of this specification, Figure 1 is a front elevational view illustrating my improved hand brake mechanism as applied to the end wall of a railway car, certain of the parts of said mechanism being indicated in dotted lines. Figure 2 is a vertical, sectional view corresponding substantially to the line 2-2 of Figure 1. Figure 3 is a vertical, sectional view in a plane substantially at right angles to the sectional view of Figure 2, and corresponding to line 3-3 of said figure. And Figure 4 is a detailed enlarged sectional view of a portion of the clutch members of my improved mechanism.

In said drawings, the end wall of the railway car is designated by 10 and my improved hand brake mechanism is preferably enclosed within a housing mounted on said end wall. In carrying out my invention, I 55 preferably provide a two part housing for the operating parts of the brake mechanism, the housing including a back plate 11 and a cover member 12. The back plate 11 is preferably provided with three securing lugs 13-13 by means of which the same is secured to the cover member 12. The cover member 12 has an outer wall 14 disposed substantially parallel to the wall formed by the plate 11 and spaced therefrom, and a side wall 15 extending along opposite sides of the housing and the top thereof, said top portion of the wall 15 being curved as shown in Figure 1. The housing is open at the bottom to accommodate the brake chain for movement, the chain being indicated by 16. The side wall 15 of the housing is provided with three outstanding lugs which register with the lugs 13 of the plate 11, these lugs also being indicated by 13. The cover member 12 is secured to the plate 11 in any suitable manner, rivets 17 being preferably employed which extend through the lugs 13-13 of the cover member and the plate 11, these rivets also serving to secure the entire housing to the wall 10 of the car, as clearly shown in Figure 2, the rivets extending through said wall 10.

My improved brake mechanism proper comprises broadly a chain winding drum A 85 having a driving gear member B formed integral therewith; a pinion C; an operating shaft D; a hand wheel E; a sliding clutch member F mounted on the shaft D and cooperating with the pinion C; and a spring 90 pressed locking dog or ratchet member G.

The chain winding drum A comprises a cylindrical section 18 on which the chain is adapted to be wound, said section being provided with an outstanding lug 19 to which 95 the inner end link of the chain is anchored. The chain 16 is connected to the operating parts of the brake mechanism in the usual manner, the connections not being illustrated in the drawings. At the outer end, the wind- 100

ing drum is provided with a flange member 20 which, together with an outstanding flange 21 at the opposite end of the cylindrical portion of the drum defines a winding space to accommodate the chain therebetween. The flange 21 is of considerably greater radius than the flange 20 and forms the gear member B, being provided with gear teeth 22 on the periphery thereof. The chain winding drum 10 A is rotatably supported on a shaft 23 having its opposite ends mounted respectively in openings provided in the front and rear walls of the housing. The openings in which the shaft 23 is journaled are preferably reinforced by suitable flanges surrounding the openings forming in effect bosses between which the chain winding drum A is held centered.

20 The operating shaft D has its opposite ends mounted in openings provided in the front and rear walls of the housing, both of said openings being reinforced by flanges surrounding the same, as clearly shown in Figure 2. The outer end of the shaft D projects a considerable distance outwardly beyond the wall 14 of the housing and the hand wheel E is mounted thereon. As shown, the outer end of the shaft D is provided with a tapered portion of substantially square cross section which fits within a tapered opening of similar cross section provided in the hub of the hand wheel E. In order to lock the hand wheel to the shaft D, the usual nut 24 is provided on the outer end of the shaft D. The major portion of the shaft is of substantially circular cross section and within the housing the shaft is provided with an integral collar portion 25 substantially midway between the front and rear walls of the housing. Between the collar 25 and the outer wall portion of the housing, the shaft is provided with a screw threaded portion 26, the threads being preferably left handed. The pinion C is rotatably supported on the cylindrical portion of the shaft D to the right of the collar 25, as viewed in Figure 2, said pinion being freely rotatable on the shaft D between said collar and the boss formed by the flange surrounding the bearing opening for the shaft D in the back plate 11 of the housing.

30 The clutch member F is of substantially cylindrical form and has threaded engagement with the threads 26 of the shaft D. At the inner end, the member F is provided with an enlarged portion 27 having ratchet teeth 37 thereon. The enlarged portion 27 is recessed at the inner end to provide a socket or seat 28 adapted to receive the outer end of the pinion C, said opening 28 being provided with internal teeth 29-29 adapted to cooperate with the teeth of the pinion C, the tooth members 29-29 being adapted to interlock with the teeth of the pinion C, whereby the outer end of the pinion and the member F together form cooperating clutch means by

which the shaft D is locked to the pinion C in order to effect rotation of the latter when winding the brake chain on the drum A. In order to hold the shaft D assembled with the housing of the brake mechanism, a retaining collar 30 is provided on the shaft D, said collar bearing on the inner side of the wall 14 of the housing and being secured to the shaft D by means of a pin 31 extending through said collar and the shaft. As will be evident, in addition to holding the shaft D assembled with the housing, the collar 30 also limits the outward movement of the clutch member F, that is, movement thereof in a lefthand direction as viewed in Figure 2.

The ratchet or locking dog G which cooperates with the ratchet teeth 37 of the clutch member F, is preferably in the form of a substantially flat spring plate having an upwardly tooth 32 thereon which engages with the teeth of the member F. The plate portion of the member G is supported at opposite ends on inwardly projecting lugs 33-33 provided on opposite side wall portions of the housing, the lugs 33 forming supporting shelves for said spring ratchet member G.

The operation of my improved hand brake mechanism in effecting tightening of the brakes is as follows: The hand wheel E, assuming the parts to be in the position shown in Figures 1 and 2, is rotated in a clockwise direction, as viewed in Figure 1, thereby effecting rotation in a similar direction of the clutch member F, which at this time is in locking engagement with the teeth of the pinion C. As will be evident, due to the action of the lefthand threaded connection between the shaft D and the clutch member F, rotation of the hand wheel in a clockwise direction tends to force the clutch member F to the right, as viewed in Figure 2, thereby causing the same to hug the enlargement or collar 25 of the shaft. The enlargement 25 preventing movement in a righthand direction of the clutch member F, as viewed in Figure 2, the same is in effect locked to said shaft. Inasmuch as the pinion C is in engagement with the gear B, the latter is rotated in a contra-clockwise direction, thereby effecting similar rotation of the chain winding drum and winding of the chain 16 on the same, thereby tightening the brakes. As will be evident, during the tightening operation of the brakes backward or retrograde rotation of the chain winding drum is prevented by the locking means G which cooperates with the ratchet teeth of the member F. The arrangement of cooperating teeth of the member F and the ratchet member G permits rotation of the member F in a clockwise direction but prevents rotation thereof in a reverse direction, thereby preventing rotation of the winding drum A in a clockwise direction. In ratcheting over the member 32, the plate member of the ratchet element G is

bowed downwardly, as viewed in Figure 3.

In releasing the brake mechanism, the hand wheel E is rotated in a contra-clockwise direction, as viewed in Figure 1. Inasmuch as the locking member G holds the clutch member F against rotation in a contra-clockwise direction, the member F will be fed outwardly on the shaft D by means of the screw threads 26. As will be evident, the teeth 29 of the member F will thus be disengaged from the teeth of the pinion C, thereby releasing the latter and permitting free running of the chain winding drum to allow unwinding of the chain therefrom and release of the brakes. Outward movement of the member F on the shaft D will be positively limited by engagement of the same with the collar 30.

Assuming that the parts of the brake mechanism are left in the condition described in the preceding paragraph, after release of the brakes, and it is desired to again apply the brakes, it is merely necessary for the operator to rotate the hand wheel in a right-hand direction. This operation of the hand wheel will effect re-engagement of the driving clutch members and further rotation of the hand wheel will then effect tightening of the brake chain. When the hand wheel E is rotated in a clockwise direction, the cooperating screw threaded connection between the shaft D and the member F will cause the latter to be moved to the right on the shaft D to re-engage the teeth 29 thereof with the teeth of the pinion C. Assuming that the teeth 29 of the member F do not exactly register with the openings between the teeth of the pinion C, when the member F is brought into abutting relation with the end of the pinion, registration of the teeth 29 with the openings between the teeth of the pinion C will be effected by rotation of the member F with the shaft D. In this connection, it is pointed out that the member F may be rotated with the shaft D through the friction of the screw threaded connection therewith, the member F being free to ratchet over the tooth of the locking member G, when the same is rotated in a clockwise direction. As soon as the teeth 29 are registered with the openings between the teeth of the pinion C, the action of the screw threaded connection between the shaft D and the member F will force the teeth 29 into the openings between the teeth of the pinion, thereby clutching the shaft D to the pinion C and causing the latter to be rotated in unison therewith, thereby driving the gear B in the manner hereinbefore described and effecting tightening of the brake chain on the winding drum A.

From the preceding description taken in connection with the drawings, it will be evident that I have provided an exceedingly simple and efficient hand brake mechanism wherein all of the operations of the same are controlled by a single manually actuated

member, in the form of a hand wheel, rotation of the hand wheel in one direction effecting tightening of the brakes and rotation in a reverse direction disengaging the driving parts so as to permit free running of the chain winding drum and complete release of the brakes. It is further pointed out that by providing interengaging clutch means, one of the members of which is actuated by the manually controlled operating mechanism to operatively engage the same with the other clutch means, and by operatively connecting the means for preventing retrograde rotation of the chain winding drum with said movable clutch member, automatic operation of the clutch mechanism is had, without in any way interfering with or changing the adjustment of the means for preventing retrograde rotation of the chain winding element.

I have herein shown and described what I now consider the preferred manner of carrying out my invention, but the same is merely illustrative and I contemplate all changes and modifications that come within the scope of the claims appended hereto.

I claim:

1. In a hand brake mechanism, the combination with a rotary tightening element; of a driving member connected thereto; a rotary operating element; cooperating clutch means on said operating element and driving member, one of said clutch means being threaded on the operating element, said last named clutch element having ratchet teeth thereon; and a locking dog cooperating with said ratchet teeth.

2. In a hand brake mechanism, the combination with a rotary chain winding drum; of a driving gear fixed thereto for rotation in unison therewith; a pinion meshing with said gear; a rotary operating shaft rotatable in reverse directions; cooperating clutch means for connecting said drive shaft and pinion, said clutch means including a member movable on said shaft and having screw threaded connection therewith, whereby the clutch member is advanced on said shaft and engaged with the other clutch member when said shaft is rotated in one direction and withdrawn therefrom when the shaft is rotated in a reverse direction; and a locking dog for preventing rotation of said movable clutch member in a direction corresponding to said reverse direction of rotation of said shaft.

3. In a hand brake mechanism, the combination with a rotary chain winding drum; of a driving gear fixed thereto for rotating the same; a pinion meshing with said gear; a rotary operating shaft; and cooperating clutch means for connecting said operating shaft and pinion for rotation in unison, said clutch means including a member having clutch teeth adapted to have clutching engagement with the pinion, said member being

- movable on said shaft and having a left-handed screw threaded connection therewith, whereby the clutch member is advanced on said shaft and engaged with the pinion when said shaft is rotated in a clockwise direction and effecting rotation of said pinion, gear, and chain winding drum during continued rotation of said shaft in clockwise direction, thereby tightening the brakes.
- 10 4. In a hand brake mechanism, the combination with a rotary chain winding drum; of a driving gear fixed to the drum for rotation in unison therewith; a pinion meshing with said gear; a rotary operating shaft rotatable in reverse directions; and cooperating clutch means for connecting said operating shaft and pinion, said clutch means including a member movable on said shaft and having clutch teeth adapted to interlock with the gear teeth of the pinion, said member having screw threaded connection with the shaft, whereby the clutch member is advanced on said shaft and engaged with the pinion when said shaft is rotated in one direction and withdrawn therefrom when the shaft is rotated in a reverse direction.
- 15
- 20
- 25

In witness that I claim the foregoing I have hereunto subscribed my name this 24th day of January, 1930.

JOHN F. O'CONNOR
